LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

CABINET CONSTRUCTION AND THE METHOD OF BUILDING THE SAME.

Application filed October 9, 1925, Serial No. 61,392. Renewed July 14, 1927.

This invention relates to a refrigerator or cabinet construction and the method of building the same, and has for its object the construction of a refrigerator which possesses all the advantages of lightness which the all-wood refrigerator has, but to all outward appearances the refrigerator is the same as a solid stone refrigerator.

Another object is the construction of an exterior coating which is of stone, and which may be very easily and quickly applied. My improved construction enables me to coat the entire exterior surface of the refrigerator with a relatively thin coating of artificial stone.

In the drawings:

Fig. 1 is a cross section through a refrigerator shell placed in a mould in preparation for casting the stone interior shell.

Fig. 2 is a similar section for showing the refrigerator removed from the mould and having the stone inner shell moulded therein, taken substantially on the line 2—2 of Fig. 3.

Fig. 3 is a vertical section through the completed refrigerator taken substantially on the line 3—3 of Fig. 2.

Fig. 4 is a sectional perspective view of the completed refrigerator.

This application is a continuation, in part, of my copending application No. 729,729 filed August 2, 1924.

The first step in the construction of the refrigerator is the building up of a refrigerator shell *a* out of wood boards, and these boards may be keyed together as at *b*. This shell comprises a plurality of side walls and the front wall *c*, which is provided with door openings *d*. The top and bottom walls *e* and *f* respectively are also formed of the same kind of wood boards and when the wood shell is complete it provides a wooden shell structure which together with the partition walls *g* form a plurality of chambers *h*. Such a box-like wood shell forms the core of the refrigerator, and I secure to the inside face of the walls of said shell, slabs of insulating material *i* such as balsa wood or cork board. This insulating material may be glued to the side walls but in practice it is found that the lining is fitted so tightly that it is unnecessary to glue or otherwise secure the slabs of insulating lining to the wall structure.

As shown in Fig. 1 this wooden shell structure is supported on a mould base *j* to which 55 is secured the cores *k*, these cores being centered within the chambers *h*, the side walls of said cores being spaced from the side walls of the box structure. Plastic artificial stone is now poured into the space between 60 the lining *i* and the cores *k* and when permitted to set and harden, forms an artificial stone coating *x* in the interior of the refrigerator forming an inner stone lining or shell for the ice and food chambers *m* and *n* 65 respectively.

This stone mixture is preferably an oxy chloride cement mixed in the following proportions, which I find suitable for the purpose: I take 20% of magnesium oxide by 70 weight (powdered form), 30% of finely ground silica by weight, and 50% of 50 mesh silica sand by weight. To this dry mix I add sufficient magnesium chloride in solution at 26° Bé. specific gravity, to obtain 75 a mixture which may be readily poured. After this interior lining or shell is allowed to set for a sufficient length of time, usually about 24 hours, the cores are withdrawn and we have a wood shell structure provided 80 with an inner stone shell.

I next secure slabs of balsa wood to the back of the refrigerator, thereby forming a wooden back panel *o* possessing very high heat insulating properties. I next fit in and 85 secure a moulding *p* to the wooden shell for holding this back panel in place.

I next coat the exterior surface of this wood shell with a relatively thin coating *y* of artificial stone and preferably apply 90 this coat by spraying the plastic stone onto the exterior surface. It is quite a problem in spraying this stone on the exterior surface to obtain a uniform thickness of stone, as this plastic stone will flow when first 95 applied to the surface if the wall on which the stone is applied is positioned on edge. To prevent this stone from running, I spray the stone onto the surface while the surface is at rest in the horizontal plane and permit 100 it to dry and harden for about 10 minutes, at which time it has set sufficiently to prevent the stone from running when this wall whose surface has just been coated is turned up 105 on edge. I therefore so support the refrigerator shell that the same may be rotated

intermittently and the walls of said shell structure successively come to rest in the horizontal plane. Obviously this shell could be rotated in any manner, but I find that it 5 may be easily turned or rotated by hand. I spray one surface at a time when the same is at rest in the horizontal plane and when it has set sufficiently I rotate the shell and bring another surface which is to be coated, 10 to rest in the horizontal plane. After all these surfaces including the back and bottom, are sprayed with this artificial stone, the same is permitted to set for a certain length of time, usually about 24 hours, and 15 I obtain a very hard and smooth artificial stone coating on the exterior surfaces, but which is very thin, usually about 1/64 of an inch or less in depth. By spraying this stone over all the exterior surfaces I conceal all 20 the joints between the different walls and between the separate boards of which the shell structure is built.

A very suitable stone mixture which I use for spraying the exterior surfaces is a 25 mix of finely powdered magnesium oxide, 25% by weight, 50% of ground silica by weight and 25% of lithophone by weight. To this dry mix I add a sufficient quantity of magnesium chloride in solution at 30 26 degrees Bé. specific gravity to form a thin plastic mixture suitable for a spray gun.

This method of applying the exterior stone coating to a wood box or shell structure, is 35 considerably cheaper than by casting the coating to the box, and it produces a box which is substantially as good as if a thicker exterior coating were applied to the shell structure. The sprayed coating may be put on very uniformly and it is possible to dry 40 the outside coating quickly, and when the same hardens it has a very smooth and hard surface which is not very easily cracked or chipped off. Preferably, I coat the stone with a waterproof coating of enamel such 45 as "Ducco" put out by the du Pont de Nemours Co. of Wilmington, Delaware. I preferably round all corners of the shell structure to permit the better adherence of the stone to the wall at the corners, as it is 50 difficult to spray a wall structure with stone, where sharp corners are used, and have the stone adhere thereto tightly enough to prevent the stone from chipping slightly at the corners.

55 Before spraying the box I preferably apply to the surface a solution of magnesium chloride of 26 degrees Bé. specific gravity. The surface is thoroughly covered with this solution in any suitable way, such as by 60 dipping, spraying or brushing it on. I then preferably rub the surface with a paint brush or some other suitable means. This, I find, is preferable as an initial step, as it establishes a better bond for the oxy-chloride 65 cement with the wood. The oxy-chloride

cement is preferably sprayed on immediately thereafter, before this solution of magnesium chloride dries out.

What I claim is:

1. A method of refrigerator or cabinet 70 construction, which comprises the building up of an outer shell structure of wood boards for defining the outer walls and the apertured partitions of the refrigerator, the applying of a stone coating to the interior surfaces of said shell structure, and the spraying of the exterior surfaces of said shell structure with stone. 75

2. A method of refrigerator or cabinet 80 construction which comprises the building up of a shell structure of wood boards to define the walls and partitions of the refrigerator, or cabinet, the casting of a stone coating on the interior surfaces of said shell structure, and the spraying of the exterior 85 surfaces of said shell structure with stone.

3. The method of refrigerator or cabinet 90 construction, which comprises the forming of an outer shell and mould of wood boards, and the cast-uniting of an inner moulded shell therein.

4. The method of refrigerator or cabinet 95 construction which comprises the forming of the outer shell and mould of wood and having a lining of heat insulating material on the inside surface thereof, and the cast-uniting of the inner moulded shell to said walls of the outer shell and mould.

5. The method of refrigerator, or cabinet 100 construction, which comprises forming an outer shell to define the walls and the chamber, or chambers of the refrigerator, lining said shell with heat insulating material to form a unit core, applying a layer of plastic stone to the shell and insulating material to form the inner walls of the refrigerator, or cabinet and applying a layer of plastic stone to the exterior surfaces of the shell to form the outer walls of said refrigerator, or cabinet.

6. The method of refrigerator, or cabinet 105 construction which comprises the forming of a core having a lining of insulating material and applying a layer of plastic stone directly to the surface of said insulating material.

7. A method of refrigerator, or cabinet 110 construction which comprises the forming of an outer shell, lining the outer shell with a layer of heat insulating material, cast uniting a layer of stone to the exposed surfaces of said insulating material and spraying the exterior surfaces of said shell structure with a layer of stone.

8. A refrigerator, or cabinet construction, 115 comprising a shell structure built up to define the refrigerator contour, a lining of heat insulating material on some of the inner walls of said shell structure and a coating of plastically applied stone on the 120

interior surfaces of said insulating material.

9. A refrigerator, or cabinet construction, comprising a core for defining the walls and partition, or partitions, of the refrigerator, said core being made up of exterior shell structure lined with insulating material, the interior walls of said refrigerator, or cabinet, being formed by a layer of stone plastically applied in part to the insulating material, and the exterior walls of said cabinet being formed by a layer of stone plastically applied to said shell.

10. A refrigerator or cabinet construction, comprising a shell structure built up of wood boards and lined with a layer of insulating material on the inside, and a coating of stone applied permanently attached over said lining to provide a stone inner shell.

11. A refrigerator or cabinet construction,

comprising a wood shell structure having an inner insulating lining, and a stone inner shell cast united therewith.

12. A refrigerator or cabinet construction, comprising a single wood shell structure having an inner insulating lining, and a stone inner shell secured therein.

13. In a refrigerator or cabinet construction, an outer shell and mould of insulated material comprising a plurality of side walls, and a moulded inner shell contacting with and cast-united thereto.

14. In a refrigerator or cabinet construction, an outer wooden shell and mould comprising a plurality of side walls provided with a lining of heat insulating material on the inside surface thereof and a front wall, and a moulded inner shell secured therein.

In testimony whereof I affix my signature.

LLOYD G. COPEMAN.
